1

This invention concerns heat-exchangers in which one of the fluids is conveyed through a plurality of ducts and the second fluid flows along passages between said ducts.

Heat-exchangers of the type wherein the ducts and passages have inner and outer defining walls of different length have heretofore suffered from the disadvantage that the ducts and/or passages have had a non-uniform width. The term "width" as used throughout this specification is to be understood as meaning the minimum distance between opposite walls of a duct or passage at any point in the heat-exchanger, said distance being measured in a plane at right angles to said defining walls.

It will be appreciated that when the duct and/or passage-width is not uniform throughout their length in the plane at right angles to said defining walls, an even distribution of one fluid throughout the other is not obtained.

It is an object of the present invention to provide a heat-exchanger of the type hereinbefore set forth in which the widths of the passages and ducts are substantially uniform so as to provide an improved distribution.

According to the present invention a heat-exchanger of the type hereinbefore set forth is characterised in that the ducts for one fluid are curvilinear viewed in the direction of the flow of the other fluid through the passages, the form of said curve being such that the width of said ducts and passages is substantially constant throughout their length in the plane at right angles to the direction of flow of the second named fluid.

According to another feature of the invention the curvature of the ducts is, or is approximately, the locus of a point on a line that rolls without sliding around a regular geometrical figure in the plane of the figure.

According to another aspect of the present invention, a heat-exchanger comprising a chamber and partitions which separate the hot and cold fluids extending inwards from the periphery towards the middle of the chamber, is characterised in that the said partitions are curved substantially to a shape as above set forth.

Preferably the curvature of the partitions or ducts is, or is approximately, the locus of a point in a straight line that rolls without sliding around a base circle, ellipse or other closed curved figure in which case the generated curve is an involute or approximates thereto. However the curvature of the converging ducts may be the locus of a point on a generating circle that rolls without sliding

2

around a base circle, ellipse or other closed curved figure in which case the generated curve is an epicycloid or a hypocycloid. It is also possible however, to generate curves having the same properties from a straight-sided non-re-entrant geometrical figure. In this latter case, the curve generated comprises two or more circular arcs, which may offer advantages from the manufacturing point of view. Instead of generating a curve in the manner just described, a suitable curve may be produced by the union of two or more circular arcs such that the complete curve approximates to the involute, epicycloid or hypocycloid form.

15 Specific embodiments of the present invention as applied to a heat-exchanger in which one of the fluids flows longitudinally through a trunk whilst the other fluid flows from the periphery of the trunk which conveys the first fluid towards the middle of the latter will now be described merely by way of example with reference to Figures 1 to 9 of the accompanying drawings whereof—

Figure 1 is a part transverse section of a heat-exchanger in accordance with the present invention in which the ducts are of involute shape,

25 Figure 2 is a similar view to Figure 1 in which the ducts are produced by the union of two circular arcs which approximate to the involute form shown in Figure 1.

30 Figure 3 is a part transverse section of another construction of heat-exchanger of drum form which is provided with ducts of involute form.

Figure 4 is a part transverse section of a heat-exchanger in which the curvature of the ducts is generated by the rolling of a straight line around a hexagon.

35 Figure 5 is a part transverse section of a heat-exchanger in which the curvature of the ducts is generated as an involute from an ellipse.

40 Figure 6 is a part transverse section of a heat-exchanger in which the ducts are of epicycloidal form.

Figure 7 is a transverse section on the line 7—7 of Figure 8 showing one quarter of the preferred 45 construction of heat-exchanger in accordance with the present invention.

Figure 8 is a section on the line 8—8 of Figure 7.

Figure 9 is a view in the direction of arrow A of Figure 8 and on a larger scale.

50 While the invention is concerned with heat-exchangers in general, a heat-exchanger in accordance with the present invention is particularly suitable for incorporation as one of the members of a gas-turbine powerplant for aircraft. The

heat-exchangers shown in Figures 1-9 inclusive are intended for this purpose.

In a heat exchanger as applied to a gas turbine power plant, the hot exhaust gases from the turbines pass through the heat-exchanger to an exit nozzle. The cold air from the compressor is delivered to and passes through the heat-exchanger so that as the exhaust gases from the turbines flow through the exchanger they will give up part of their heat-content to the cold air thereby heating the latter before it reaches the combustion chambers.

In the particular application of the invention referred to, three factors are of especial importance, namely:

(i) That whilst the pressure-drop entailed across the "cold" side of the exchanger is of relatively little importance the pressure-drop across the "hot" side is material; the latter must therefore be kept at a minimum. With this end in view the exhaust-gases from the turbine should follow a straight path to the discharge nozzle; however, the air passing from the compressor to the heat-exchanger and thence to the combustion-chamber may without undue effect follow a circuitous path.

(ii) That of ensuring uniformity of distribution from the compressor and of supply to the turbine. This requires that as great a number of outlets be spaced around the delivery chamber of the compressor as is practicable, and that a similar disposition of inlets to the turbine be provided,

(iii) That the cross-sectional area of the ducts (and of the passages between them) be constant throughout their length in the plane at right angles to the direction of the passages between the ducts and that the width of both ducts and passages, as hereinbefore explained, be substantially uniform for the "hot" and "cold" sides of the exchanger. This ensures that the transfer of heat for any given size of heat-exchanger is a maximum.

In each of the constructions shown in Figures 1 to 6 of the accompanying drawings the exhaust-gases from the turbine pass by a straight path longitudinally through a trunk 11 whose peripheral or outer defining wall is indicated at 12. In this way the first factor mentioned above is satisfied. The cold air from the compressor is delivered to a plurality of chambers 13 which are spaced around the wall 12 and extend along the length of the drum—one end of each of the chambers is connected with the compressor and the other end is closed. The air passes from chambers 13 into a plurality of ducts 14 which extend towards the middle of the trunk and into chamber 15, and then into a plurality of ducts 16 which lead into chambers 18. The latter, which are spaced around the wall 12 (being intercalated with chambers 13) and extend along the length of the drum, are connected to the turbine. The provision of a plurality of inter-calated cold and hot-air chambers 13 and 18 which are spaced around the peripheral wall 12 of the heat-exchanger ensures uniformity of distribution from the compressor and to the turbine and thus meets factor (ii) referred to above. It is clear from the drawings that the exhaust-gases which pass longitudinally through the trunk 11 are constrained to flow through a plurality of passages 19 each of which is bounded by a pair of adjacent ducts. In this way the hot exhaust-gases are brought into intimate contact with the air in ducts 14 and 16 thereby heating the air which passes from the

cold-air chambers 13 to the hot-air chambers 18.

It will be understood from this general description of the heat-exchangers shown in Figures 1 to 6 that the exhaust-gases flow through the passages 19 in a direction normal to the plane of the paper. The width of the ducts and passages will be measured (in accordance with the definition set forth above) in the plane of the paper and will be the minimum distance between the bounding walls of the ducts and passages in said plane.

The present invention aims at providing a particular arrangement of ducts and passages which will have a constant or approximately constant width throughout their length in the plane of the paper.

In Figure 1 the ducts 14, 16 which in this construction extend from the wall 12 of trunk 11 to inner defining wall 17 of a central collector 15 lie upon a curved path. The curvature of the ducts is generated by the rolling of a straight line around the wall of the central collector 15, that is the ducts 14, 16 are of an involute shape. As is clearly shown in Figure 1, with this construction the provision of ducts of uniform width throughout their length (as occurs when the ducts are made from parallel-wall tube of diameter a) will result in the passage width b also being constant throughout the length of the ducts. Accordingly a heat-exchanger constructed as shown in Figure 1 will completely satisfy the three conditions stated to be essential in a heat-exchanger for a gas turbine power-plant.

In the construction shown in Figure 2 the curvature of the ducts 14, 16 is produced by the union of two circular arcs so as closely to approximate to the involute form shown in Figure 1. The portion of the ducts which lies adjacent the wall 17 is a circular arc having a radius R^1 whilst the portion of the ducts adjacent the wall 12 is a circular arc whose radius is equal to R^2 . With this construction the duct width a may be made uniform by constructing the ducts from parallel-wall tube and although the passage width b is not absolutely constant throughout the length of the ducts 14, 16, by suitably selecting the radii R^1 and R^2 it is possible so to arrange matters that the passage width will vary by only a small amount over the length of the ducts. Any disadvantage which may accrue from such non-uniformity in the width of the passages may be off-set from the manufacturing point of view.

The shape of the ducts 14, 16 shown in Figure 3 being of involute form and the ducts having a uniform width a throughout their length it follows that the passage width b will also be constant throughout the length of said ducts. In this construction the central collector 15 has been dispensed with and the cold air flows directly from one of the cold-air chambers 13 to its associated hot-air chamber 18, along a duct which is substantially U-shaped. The limbs 14, 16 of each duct (which are of involute form) have their inner extremities connected by an arcuate portion 20 so that the cold air from chamber 13 will pass down limb 14 of the duct, around the portion 20 and up the other limb 16 to the hot-air chamber 18. It will be noted from Figure 3 that the U-shaped ducts are stacked one within the other, and that all the limbs 14 of each stack are associated with a cold-air chamber 13 whilst the limbs 16 of each stack are associated with the adjacent hot-air chamber 18. The inner ends

of the passages 19 for the exhaust gases are bounded by a wall 21.

In the construction shown in Figure 4 the central collector 15 is hexagonal in cross-section and the ducts 14, 16 are generated by the rolling of a straight line around the hexagonal chamber. As a consequence the ducts are formed by the junction of a number of circular arcs each of which has its centre at one of the corners of the hexagon. The portion of the ducts 14, 16 which lies adjacent the hexagonal collector 15 and between side 17 of the latter and the line c, for instance, consists of a plurality of concentric arcs, the centre of which is at d. The portion of said ducts lying between side 17' of the collector, the line c and the line c' consists of a plurality of concentric circular arcs whose common centre lies at d'. In this construction with a preselected uniform duct width a the passage width b will be constant throughout the length of the ducts.

Figure 5 shows a similar construction to that of Figure 1 in so far as the ducts 14, 16 are of involute form. Instead of the involute being generated from a circular collector as is the case in Figure 1, the base for the involute is an elliptical collector 15. Since the ducts are of involute form the selection of a uniform duct width a will result in the passage width b also being uniform throughout the length of the ducts.

Figure 6 shows a construction in which the curvature of the ducts is generated by the rolling of a circle e about a circular collector 15 so that, for instance, point f on the circle describes path g which is the path followed by the ducts 14, 16. In this construction the ducts 14, 16 are of epicycloidal form and are such that by providing a constant duct width a the passage width b will be approximately constant throughout the length of the ducts provided that the diameter of the rolling circle is great compared with that of the collector 15. As between ducts of the form shown in Figure 6 and ducts of involute form it is found that for the same drum and central collector diameters the epicycloidal duct is the longer of the two. The length of an epicycloid 45 duct is dependent upon the diameter of the rolling circle e so that it is possible by selecting a suitable diameter for the rolling circle e to determine the length which the ducts 14, 16 shall have, irrespective of the diameters of the trunk 11 and collector 15. This is particularly advantageous when due to other circumstances these diameters are fixed.

It will be appreciated that similar curves to those shown in Figures 1 to 6 may be produced by the rolling of a circle around the central collector 15 said circle being of larger diameter than the collector and lying outside and in point contact with said collector. The curve thus generated is a hypocycloid and has similar properties to the epicycloid, namely that by selecting a uniform duct width a the passage width b will be approximately constant throughout the length of the ducts.

Various modifications to the construction of heat-exchanger shown in Figures 1 to 6 inclusive may be made whilst retaining the essential features of the invention in which uniformity of width is provided for the ducts and passages. For instance as shown in Figure 2 the collector 15 may have an inner bounding wall 21 so that said central chamber is of annular form. This construction is particularly suitable where it is desired to pass a transmission or other shaft 22 centrally through the heat-exchanger. The wall

of the collector 15 in Figure 4 may be cylindrical as indicated at 37, the cylinder being circumscribed about the hexagon used to generate the ducts 14 and 16. The figures used to generate the ducts may be an equilateral triangle, square or any regular polygon. It will be appreciated from Figure 5 that the cold and hot-air chambers 13, 18 instead of being concentric with the long axis of the heat-exchanger may lie upon an elliptical wall 23. Alternatively whilst the hot and cold-air chambers lie upon said ellipse the central chamber may be circular in cross-section. In the construction shown in Figures 1, 2, 4 and 5 the cold air passing inwardly along ducts 14 is discharged into a common chamber. In certain cases it may be found preferable to ensure that the cold air from one of the chambers 13 passes to its associated hot-air chamber 18 without mixing in collector 15 with the gases from the other cold-air chambers. To this end the central chamber may be provided with a spider 24 (Figure 6) whose radial arms extend outwardly to form a plurality of sealed compartments 25 each of which is associated with a cold-air chamber and a hot-air chamber.

When the ducts 14, 16 shown in any of the constructions of Figures 1 to 6 are made from parallel wall tubes it is arranged that banks of such tubes extend along the length of the heat-exchanger trunk, the tubes of the various banks being aligned so as to provide straight-through passages 19 for the exhaust gases.

As an alternative to the provision of tubular ducts 14, 16 said ducts may be formed in pairs of plates which extend lengthwise through the trunk 11, and viewed endwise (that is in the direction of flow of the exhaust gases) are curved to one of the shapes described with reference to Figures 1 to 6. Each plate of a pair is crimped at intervals along its length so as to abut the other plate and is united thereto, the crimps extending from the edge of the plate which is secured to the wall 17 of the collector 15 to the edge which is secured to the wall 12 of the trunk 11. There is thereby provided a unit which comprises a plurality of ducts side-by-side open at one end to the interior of the collector 15 and at the other end to a cold-air chamber 13 or a hot-air chamber 18. Since each unit or pair of plates extends along the length of the trunk 11, it provides a row of ducts which are placed one behind the other viewed endwise of the trunk. It will be obvious that with this arrangement also, the units will provide straight-through passages 19 for the exhaust gases, these passages being formed between the adjacent plate units.

The preferred embodiment of the present invention is shown in Figures 7, 8 and 9 of the accompanying drawings.

Referring to Figure 8 it will be noted that the ends of the heater are closed by plates 26 between which a plurality of parallel tubes 27 extend. The exhaust gases from the turbine pass through said tubes to the discharge nozzle. The end plates 26 are formed around their circumference with a plurality of spaced ears 31 each of which is adapted to support a hood 33 that extends from an ear associated with one plate to a corresponding ear associated with the other end plate. Each hood assemblage constitutes one of the hot or cold-air chambers 18 and 13 referred to above. The air from the compressor (and to the turbine) is carried by pipes (not shown) which are attached to flanges 32. The air from the compressor is delivered to the cold-

air chambers 13 and then passes inwardly between the tubes 27 to a collector 15 disposed at the middle of the heat-exchanger. The partially heated air then flows outwardly from the collector between another series of the tubes 27 to the hot-air chamber 18 which is in communication with the turbine.

As shown in Figure 7 the tubes 27 are arranged side by side in a plurality of rows generally indicated at 36. Each row is formed by locating the centres of a number of said tubes upon an involute curve as viewed in the direction of flow of the exhaust gases through the tubes. The plurality of tubes 27 which constitutes one of the rows 36 is equivalent to the passage 19 referred to in the descriptions of Figures 1 to 6 whilst the spaces between the rows (along which is conveyed the cold air from the chambers 13 and the partially heated air moving towards chambers 18) are equivalent to the ducts 14 and 16. It will be appreciated from Figure 7 that the passage width b being predetermined is uniform throughout the length of the rows. With this uniform passage width and with the tubes 27 disposed in involute rows the width a of the ducts 14, 16 is also uniform throughout their length.

The tubes 27 are oval in cross-section the shorter distance between opposite walls being equal to the passage width b . In order to provide adequate support for the multiplicity of tubes the end plates 26 are formed with involute slots 28 and a flange 29 bounding said slots. The ends of the tubes 27 are received by the slots 28 and flanges 29. The abutting faces of adjacent tubes in the rows are maintained in contact by a packing piece 30 which is inserted if required at the outer end of the slots 28. So that the tubes 27 may form a gas tight connection with the involute slots 28 by which they are carried the ends of the tubes are upset into a trapezoidal cross-section (see Figure 9). As a consequence the abutting faces of adjacent tubes 27 are brought into intimate contact with each other whilst the faces of the tubes which engages the sides of the involute slots 28 make good contact therewith. When the trapezoidal ends of the tubes 27 are brazed or welded into the slots 28 a gas-tight joint is obtained. For convenience there has been shown in Figure 7 an involute slot 28 which is devoid of the pipes 27, and an involute slot 28 showing the disposition of the trapezoidal ends of the tubes 27 therein.

The plates 26 (as shown in Figure 8) extend completely across the ends of the heat-exchanger so that the exhaust gas is constrained to flow along the tubes 27 being prevented by said plates from mixing with the air passing along either the ducts 14, 16 or with the air in the collector 15.

In the construction shown in Figures 7 and 8 the tubes 27 may be replaced by pairs of plates bent to an involute shape as described in one of the constructions above, the plate being crimped and united with the crimps extending parallel with the flow of the exhaust gases through the heat-exchanger.

Although in each of the embodiments described above the collector 15 is coincident with the base from which the curve for the ducts is generated this need not be so. The collector may be of greater or less diameter than said base. Moreover, the regular geometrical figure forming the base for the generation of said curve may in certain cases be different from the geometrical outline of the collector.

I claim:

1. A heat-exchanger comprising a plurality of

spaced ducts for one fluid extending from the periphery of said exchanger toward the axis thereof and forming passages between said ducts through which another fluid flows axially of said exchanger, the walls separating said ducts and passages being so curved in planes at right angles to said axis that said ducts and passages are of substantially uniform width when measured in planes at right angles to said axis, a plurality of inlet headers disposed around said heat-exchanger and communicating with the outer end of some of said ducts, and a plurality of outlet headers disposed around said heat-exchanger and intercalated with said inlet headers, said outlet headers communicating with the outer ends of the remaining ducts and said last named ducts communicating with the inner ends of the ducts in communication with said inlet headers.

2. A heat-exchanger comprising a plurality of spaced ducts for one fluid extending from the periphery of said exchanger toward the axis thereof and forming passages between said ducts through which another fluid flows axially of said exchanger, the walls separating said ducts and passages being so curved in planes at right angles to said axis that said ducts and passages are of substantially uniform width when measured in planes at right angles to said axis, a plurality of inlet headers disposed around said heat-exchanger and communicating with the outer end of some of said ducts, and a plurality of outlet headers disposed around said heat-exchanger and intercalated with said inlet headers, said outlet headers communicating with the outer ends of the remaining ducts and said last named ducts communicating with the inner ends of the ducts in communication with said inlet headers.

3. A heat-exchanger comprising a plurality of spaced ducts for one fluid extending from the periphery of said exchanger toward the axis thereof and forming passages between said ducts through which another fluid flows axially of said exchanger, the walls separating said ducts and passages being so curved in planes at right angles to said axis that said ducts and passages are of substantially uniform width when measured in planes at right angles to said axis, the curvature of said walls conforming to the locus of a point on a line that rolls without sliding around a regular geometrical figure in a plane at right angles to the axis, a plurality of inlet headers disposed around said heat-exchanger and communicating with the outer end of some of said ducts, and a plurality of outlet headers disposed around said heat-exchanger and intercalated with said inlet headers, said outlet headers communicating with the outer ends of the remaining ducts and said last named ducts communicating with the inner ends of the ducts in communication with said inlet headers.

4. A heat-exchanger comprising a plurality of spaced ducts for one fluid extending from the periphery of said exchanger toward the axis thereof and forming passages between said ducts through which another fluid flows axially of said exchanger, the walls separating said ducts and passages being so curved in planes at right angles to said axis that said ducts and passages are of substantially uniform width when measured in planes at right angles to said axis, the curvature of said walls conforming to the locus of a point on a circle that rolls without sliding around a regular geometrical figure in a plane at right angles to said axis, a plurality of inlet headers

disposed around said heat-exchanger and communicating with the outer end of some of said ducts, and a plurality of outlet headers disposed around said heat-exchanger and intercalated with said inlet headers, said outlet headers communicating with the outer ends of the remaining ducts and said last named ducts communicating with the inner ends of the ducts in communication with said inlet headers.

5. A heat-exchanger comprising a plurality of spaced ducts for one fluid extending from the periphery of said exchanger toward the axis thereof and forming passages between said ducts through which another fluid flows axially of said exchanger, the walls separating said ducts and passages being so curved in planes at right angles to said axis that said ducts and passages are of substantially uniform width when measured in planes at right angles to said axis, the curvature of said walls conforming to circular arcs that approximate to the locus of a point on a line that rolls without sliding around a regular geometrical figure in a plane at right angles to said axis, a plurality of inlet headers disposed around said heat-exchanger and communicating with the outer end of some of said ducts, and a plurality of outlet headers disposed around said heat-exchanger and intercalated with said inlet headers, said outlet headers communicating with the outer ends of the remaining ducts and said last named ducts communicating with the inner ends of the ducts in communication with said inlet headers.

6. A heat-exchanger comprising a plurality of spaced ducts for one fluid extending from the periphery of said exchanger toward the axis thereof and forming passages between said ducts through which another fluid flows axially of said exchanger, the walls separating said ducts and passages being so curved in planes at right angles to said axis that said ducts and passages are of substantially uniform width when measured in planes at right angles to said axis, the curvature of said walls conforming to the locus of a point on a circle that rolls without sliding around a regular geometrical figure in a plane at right angles to said axis, a plurality of inlet headers disposed around said heat-exchanger and communicating with the outer end of some of said ducts, and a plurality of outlet headers disposed around said heat-exchanger and intercalated with said inlet headers, said outlet headers communicating with the outer ends of the remaining ducts and said last named ducts communicating with the inner ends of the ducts in communication with said inlet headers.

7. A heat-exchanger comprising a plurality of spaced ducts for one fluid extending from the periphery of said exchanger toward the axis thereof and forming passages between said ducts through which another fluid flows axially of said exchanger, the walls separating said ducts and passages being so curved in planes at right angles to said axis that said ducts and passages are of substantially uniform width when measured in planes at right angles to said axis, the passages between said ducts being composed of axially extending tubes disposed side by side to constitute chains, a plurality of inlet headers disposed around said heat-exchanger and communicating with the outer end of some of said ducts, and a plurality of outlet headers disposed around said heat-exchanger and intercalated with said inlet headers, said outlet headers communicating with the outer ends of the remaining ducts and said last named ducts communicating with the inner ends of the ducts in communication with said inlet headers.

last named ducts communicating with the inner ends of the ducts in communication with said inlet headers.

8. A heat-exchanger comprising a plurality of spaced ducts for one fluid extending from the periphery of said exchanger toward the axis thereof and forming passages between said ducts through which another fluid flows axially of said exchanger, the walls separating said ducts and passages being so curved in planes at right angles to said axis that said ducts and passages are of substantially uniform width when measured in planes at right angles to said axis, the passages between said ducts being composed of axially extending tubes disposed side by side to constitute chains, a plurality of inlet headers disposed around said heat-exchanger and communicating with the outer end of some of said ducts, a plurality of outlet headers disposed around said heat-exchanger and intercalated with said inlet headers, said outlet headers communicating with the outer ends of the remaining ducts and said last named ducts communicating with the inner ends of the ducts in communication with said inlet headers, and plates provided with curved slots in which the ends of said tubes are disposed.

9. A heat-exchanger comprising a plurality of spaced ducts for one fluid extending from the periphery of said exchanger toward the axis thereof and forming passages between said ducts through which another fluid flows axially of said exchanger, the walls separating said ducts and passages being so curved in planes at right angles to said axis that said ducts and passages are of substantially uniform width when measured in planes at right angles to said axis, the passages between said ducts being composed of axially extending tubes disposed side by side to constitute chains, a plurality of inlet headers disposed around said heat-exchanger and communicating with the outer end of some of said ducts, a plurality of outlet headers disposed around said heat-exchanger and intercalated with said inlet headers, said outlet headers communicating with the outer ends of the remaining ducts and said last named ducts communicating with the inner ends of the ducts in communication with said inlet headers, and plates provided with curved slots in which the ends of said tubes are disposed with the walls of the adjacent tubes in contact.

10. A heat-exchanger comprising a plurality of spaced ducts for one fluid extending from the periphery of said exchanger toward the axis thereof and forming passages between said ducts through which another fluid flows axially of said exchanger, the walls separating said ducts and passages being so curved in planes at right angles to said axis that said ducts and passages are of substantially uniform width when measured in planes at right angles to said axis, said walls being crimped together in pairs to form tubes constituting axially extending passages and disposed in a side by side chain-like arrangement, a plurality of inlet headers disposed around said heat-exchanger and communicating with the outer end of some of said ducts, and a plurality of outlet headers disposed around said heat-exchanger and intercalated with said inlet headers, said outlet headers communicating with the outer ends of the remaining ducts and said last named ducts communicating with the inner ends of the ducts in communication with said inlet headers.

11. A heat-exchanger comprising a plurality of

11

spaced ducts for one fluid extending from the periphery of said exchanger toward the axis thereof and forming passages between said ducts through which another fluid flows axially of said exchanger, the walls separating said ducts and passages being so curved in planes at right angles to said axis that said ducts and passages are of substantially uniform width when measured in planes at right angles to said axis, a plurality of inlet headers disposed around said heat-exchanger and communicating with the outer end of some of said ducts, a plurality of outlet headers disposed around said heat-exchanger and intercalated with said inlet headers, said outlet headers communicating with the outer ends of the remaining ducts and said last named ducts communicating with the inner ends of the ducts in communication with said inlet headers, and an inner axially extending chamber constituting a means of communication between the ducts respectively communicating with the inlet and the outlet headers.

12

12. A heat-exchanger as defined in claim 8 wherein at least the ends of the tubes are of trapezoidal cross section to completely fill the slots.
